UNITED STATES PATENT OFFICE.

JOSEPH A. MURENA, OF NEW YORK, N. Y.

CUSHION DEVICE FOR SHOES.

1,127,913.

Specification of Letters Patent.

Patented Feb. 9, 1915.

Application filed May 16, 1913. Serial No. 768,108.

To all whom it may concern:

Be it known that I, JOSEPH A. MURENA, a subject of the King of Italy, residing at New York, in the county of New York and 5 State of New York, have invented new and useful Improvements in Cushion Devices for Shoes, of which the following is a specification.

This invention relates to cushion devices 10 for shoes; and it has for its primary object the provision of a device of this character which may be readily applied to the shoe and associated with the heel portion thereof so as to furnish to the foot the maximum 15 buoyancy and for properly absorbing the shocks and jars.

Another object of the invention is the provision of means carried directly by the cushion and operable in connection with the 20 insole of the shoe for holding the cushion against creeping longitudinally.

With these and other objects in view, the invention consists of certain novel features of construction, combination and arrangement of parts, as will be hereinafter described and claimed.

In the accompanying drawings:—Figure 1 is a side view of a shoe, showing a part thereof broken away and illustrating the 30 application of the cushion in the heel; Fig. 2 is a top plan view of the device; Fig. 3 is a bottom plan view thereof; and Fig. 4 is a section on line 4—4 of Fig. 1.

The device comprises a cushion 1 constructed of rubber and provided with concentrically arranged inner supporting ribs 2 and an outer substantially oval rib 3, all of the ribs being of a diminishing height toward the front of the shoe, while the body 40 of the cushion is curved longitudinally so as to adapt itself to the formation of the heel and the adjacent portion of the instep of the insole, as clearly shown in Fig. 1. The rubber body forming the cushion has a 45 forward extension 4 overlying the inner portion of the insole immediately at the instep or at the point of juncture thereof with the heel. A strip of leather 5 of a configuration in plan conforming with that of the 50 rubber cushion overlies the latter and at the forward end said material is extended directly over the portion 4 of the cushion and

riveted thereto, as at 6. A relatively flexible strip of material 7, such as metal is extended beneath the portion 4 of the cushion 55 and secured thereto by rivets 6 above referred to. This strip forms a securing means whereby the cushion may be properly held within the shoe at a point directly over the heel and positively secured against longitudinal creeping or accidental derangement. The ends of the strip 7 are extended beyond the sides of the cushioning device, as at 8, providing bendable portions which may be folded under the insole of the shoe, 65 as clearly illustrated in Fig. 4 of the drawing. From this construction it is evident that the ribs 2 and 3 of the main body member of the device serve to yieldingly support the heel of the foot and to correctly absorb 70 shocks and jars which may be imparted to the shoe. It is obviously seen that through the provision of the metallic strip 7 the device may be readily attached to any form of shoe without necessitating changing the 75 construction thereof. While the strip 7 is especially desirable for use in connection with a cushion of the character described, it is stated that the same may be used in connection with arch supporters and the 80 ends of the strip connected with the insole so as to hold the supporter against shifting in the shoe.

From the foregoing description, taken in connection with the accompanying drawings, the construction and operation of the invention will be readily understood without requiring a more extended explanation.

Various changes in the form, proportion and the minor details of construction may 90 be resorted to without departing from the principle or sacrificing any of the advantages of this invention as claimed.

Having thus described my invention, what I claim is:—

The herein described cushioning device for shoes comprising a yieldable cushion shaped to fit in the heel and having a forward extension to bear on and partly overlap the shank of the shoe, a cover of flexible material on the cushion, a continuous metallic strip arranged transversely of the forward extension of the cushion and between the same and the corresponding part

of the cover, said metallic strip being spaced from the extreme front end of the cover and having bendable ends extending beyond the sides of the cushion and arranged to be removably inserted under the insole, and fastening devices securing said cover, strip and cushion together.

In testimony whereof I affix my signature in presence of two witnesses.

JOSEPH A. MURENA.
